UNITED STATES PATENT OFFICE

GLENN J. BARRETT, OF CHICAGO, ILLINOIS, ASSIGNOR TO PORTABLE ADDING MACHINE COMPANY, OF CHICAGO, ILLINOIS

MANUAL PAPER FEEDING MECHANISM FOR ADDING MACHINES

Application filed December 24, 1928. Serial No. 328,257.

My invention relates to improvements in tape or paper manual feeding mechanisms for adding machines or any machine requiring a continuous paper or tape.

5 The object of this invention is to provide a convenient means for manually advancing the paper or tape when the mechanism of the machine to which it is adapted is completely enclosed and when the case is opened 10 for manipulation or adjustment, whether said machine may have a stationary paper feeding platen mechanism, or one adapted to swing forward to printing position, for example, like the well known Corona adding machine.

20 Objects pertaining to details appear from the description to follow. My invention is pointed out in the claims. Structures embodying the same are clearly shown in the accompanying drawings, in which:

Fig. 1 is a right side perspective view and shows the twirler knob of my invention extending from the enclosing case of an adding machine.

25 Fig. 2 is a left side detail perspective view and shows the lid of the adding machine tilted back exposing the paper feed mechanism of my invention.

Fig. 3 is an enlarged detail elevation view 30 of the train of connecting gears and adjusting block from the outside twirler knob.

My invention is particularly adapted to the paper feed of an encased adding machine or any machine requiring a continuous tape 35 or paper, where said casing completely covers the machine. It avoids the necessity of uncovering any portion of the machine in order to manually feed the paper up to a point where it may be inspected or torn off 40 and at the same time provides similar effective paper feed when the casing is opened.

1 is the forward portion of an enclosing case. 2 is the lid for inspecting the interior hinged at 3. 4 is an opening in the lid 45 covered with glass for inspecting the printing. 5 is the platen around which the paper is fed. 6 is a window opening in the lid through which the paper may be fed. 7 is the paper strip itself which projects in 50 Fig. 1 as it leaves the machine. 8 is the

frame supporting the platen. 9A is the knob upon the outside of the case for manually feeding the paper through the opening 6. 10 is the pinion attached to the platen shaft 11 to which is attached the knob 9. Fig. 3 shows only a portion of the teeth of said pinion 10. It will be understood that teeth complete the dotted arc.

Fig. 3 shows the platen pinion 10 in engagement with the idler 12 pivotally mounted upon the adjustable block 13 carried by the side wall of the case. 14 is the main actuating pinion rigidly attached to the actuating shaft 15 which is journaled in the block 13 and extends through the right side of the lid 2 to which shaft 15 is attached the knob 9A. The actuating pinion 14 is also shown with incompletely teeth for convenience. It will be understood that teeth completely fill the dotted arc.

16 is a stud extending from the inside of the side wall of the lid 2 and through a slot 17 in the block 13 for adjustment. 18 is a lock nut firmly clamping the block 13 in proper adjusted position. The block 13 is 75 adapted to pivot upon the shaft 15, said slot 17 being in an arc concentric with the center of said shaft 15 and the object of this arrangement is to provide an adjustment between the idler pinion 12 and the platen 80 pinion 10 so that when the lid is replaced, as shown in Fig. 1, the mesh of the teeth will be perfect.

19 is a spring catch pivoted to the lid at 20. 21 is a finger piece for unlatching this catch when it is desired to elevate the lid. 22 is the pin, shown in dotted lines in Fig. 1, upon which said latch locks the lid firmly in position so that the manual feeding of the paper will not disturb the lid. The spring 85 23 upon the latch 19 exerts a tension upon the latch 19 to hold the same firmly engaged with the pin 22 in the forward portion of the case 1.

It will be readily seen that my invention 90 admits of turning the platen manually with the lid closed by turning knob 9A (see Fig. 1), and that the direction of turning will be the same as that of the knob 9 (see Fig. 2) attached directly to the platen shaft 200

11. It will be further understood that my invention admits of hinging a case as shown, and also of swinging the platen to printing point when applied to a machine like the 5 Corona adding machine in which it is understood the platen frame 8 mounted in the machine, is adapted to swing forwardly to the printing point.

In case of a swinging platen just mentioned, it will be understood that the platen pinion 10 starts from position shown in Fig. 3 and swings forwardly with the platen frame, and returns to same position as shown in Fig. 3. There being no 15 tension whatever upon the actuating pinion 14 nor the idler 12, the teeth of 12 and 10 readily remesh upon the return of the platen to normal position.

Having thus described my invention, what 20 I claim as new and desire to secure by Letters Patent, is:

1. In combination with a movable case enclosing a printing platen and paper tape of an adding machine or similar device, of a 25 disconnectable means for manually feeding said paper comprising a feeding knob or finger piece outside said case, an actuating pinion attached thereto, an adjustable idler pinion always in mesh with said actuating 30 pinion, and a pinion connected to said printing platen normally in mesh with said idler pinion which is separable therefrom.

2. In combination with a movable case enclosing a printing platen and paper tape 35 of an adding machine or similar device, of a disconnectable means for manually feeding said paper comprising a feeding knob or finger piece outside said case, an actuating pinion attached thereto, an idler pinion 40 always in mesh with said actuating pinion, and a pinion connected to said printing platen normally in mesh with said idler pinion which is separable therefrom.

3. In combination with a movable case 45 enclosing a printing platen and paper tape of an adding machine or similar device, of a disconnectable means for manually feeding said paper comprising a feeding knob or finger piece outside said case, an actuating 50 pinion attached thereto, and a printing platen with pinion within the said case with disconnectable gear to the actuating pinion, as specified.

In witness whereof I have hereunto set 55 my hand.

GLENN J. BARRETT.
